UNITED STATES PATENT OFFICE.

JOHN S. SMITH, OF JACKSON, MICHIGAN.

REVOLVING TABLE FOR TILE-MILLS.

SPECIFICATION forming part of Letters Patent No. 267,760, dated November 21, 1882.

Application filed July 27, 1882. (No model.)

To all whom it may concern:

Be it known that I, JOHN S. SMITH, a citizen of the United States, residing at Jackson, in the county of Jackson and State of Michigan, have invented certain new and useful Improvements in Revolving Tables for Tile-Mills, of which the following is a specification, reference being had therein to the accompanying drawings.

10 This invention relates to improvements in the process and the mechanism for removing tiles (after they have been formed and cut) in such manner that they shall not be damaged nor have their shape marred.

15 It consists partly in a method of removing tiles from the forming and cutting mechanism in such manner that the tiles shall be supported both on the inside and the outside to prevent marring and misshaping, and so change 20 the position of the tile that it can be removed from the machine without danger.

It consists, further, in a series of revolving tables mounted upon the axis, one table being presented at a time to receive a tile. After a 25 tile has been received and cut off the proper length, it is lifted upward from a horizontal position to a vertical.

It consists, further, in various details adapted to carry out the object above described.

30 Figure 1 is a side elevation of a machine embodying my improvements. Fig. 2 is a top plan view. Fig. 3 is a sectional view on line x x , Fig. 1. Fig. 4 is a section of the upper frame on the line y y , Fig. 2. Figs. 5, 6, and 35 7 show the interior supporting-drum. Fig. 8 is a view of the spring-catch and one of the troughs while in engagement therewith.

The machine or the parts thereof essentially intended to carry out my invention may be 40 combined with a tile-mill of any of the well-known forms, or with one of any preferred character. It may be mounted upon a framework of any suitable character more or less different from that shown.

45 In the drawings I have shown a main supporting-frame constructed of the uprights or legs A A, the sills or longitudinal pieces B B, and the cross-pieces C C. The legs or supports

50 A A may be permanently fastened to the other parts of the frame; or they may be detachably connected thereto, and also may be used in such

manner that the height of the machine can be adjusted upon them. Upon this frame is mounted another adapted to be moved up and down to a limited extent, the latter frame consisting of the side pieces, A', and the cross-pieces B' B'. These two frames are connected by means of links n^2 n^2 and curved connecting arm or bar N'. The said bar is slotted, as at n' , and pivoted at n to the upper frame, there being a set-screw, n^3 , in the slot n' , by which the frame A' B' may be supported in any desired position.

55 N is an adjustable handle carried by the frame N', and pivoted at n^4 to the frame B. 60 By means of this the adjustment can be readily and instantly made.

A sliding frame is supported upon the frame A' B' and arranged to carry the revolving tile-support. It is constructed of side bars, A², 70 and an end bar, B², and is mounted upon the frame A' B', preferably by means of rollers A³, which permit it to easily slide upon the lower frame. Upon this frame is mounted a transverse shaft, D. To the shaft are secured four 75 troughs, E E E E, or recessed plates, they being situated at substantially ninety degrees apart.

At one of the frames A² A² there is arranged a cut-off mechanism. Preferably it consists of 80 an arched plate, F, provided with a slot, f, and the wire-carrying arm G. The wire g is so arranged that as the arm or handle G is caused to traverse the arched plate F the wire cuts the tube of clay and forms a tile of the proper 85 length. In the construction shown in the drawings the wire has its lower end attached to an eye, g', which is connected by a hinge with the spring g², the spring being arranged to yield somewhat, so that when the wire comes in contact with small stones or other hard substances in the clay the wire may yield sufficiently to prevent a marring of the tile. At the upper end the wire is attached to an eye or hook, a², 90 at the lower end of a threaded hook, h³. This threaded rod is held in the carrying-arm, G, which is provided with a longitudinal aperture to receive it.

95 h⁴ is a thumb-nut engaging by thread-connection with the rod h³, and by means of it the tension of the wire may be delicately adjusted.

The wire-carrying arm G is cast with or se-

cured to a curved plate, G' , which conforms as accurately as possible to the outer face of the arched plate F , it being formed with lugs or ears h^5 , which are turned down and under the plate F to provide a clamp to hold the plate F in place. The inner end of the wire-carrying rod h^3 moves back and forth in the slot j . However, I do not limit myself to this exact form of cutter, for some of the features of my machine may be embodied without its being restricted to this form of cutter, though I find that my form possesses advantages when combined in the way shown with the parts to be hereinafter described.

15 Before the tile is cut the frame $A^2 B^2$ is moved up into proper position relatively to the tile-mill. As the tile issues from the mill it is deposited upon the trough or curved plate E , that has been brought up to receive it. It moves 20 along said trough or plate until it strikes against a removable plate, I , that is placed against the back of the trough E , which is in a vertical position. After it strikes against the vertical plate I the upper frame moves 25 relatively to the lower frame, and the tile is then cut. As soon as cut the shaft D is revolved one-quarter of a revolution, which brings the tile from the horizontal position into the vertical position, it resting, after being brought 30 into the vertical position, upon the removable plate I . It can be readily taken away while standing vertically by removing the plate I , which has now been brought into a horizontal position. Throwing the tile into the vertical 35 position, and with it the trough with which it is in contact, brings the next trough or curved plate into a horizontal position proper to receive the next tile. Before the next tile has been entirely received upon the trough the 40 upper frame should be removed back into its original position relative to the tile-mill.

It will be seen that the four troughs $E E E$ form a revolving table, and that each part of the table in turn receives a tile in a horizontal position and raises it on end before it is removed from the table.

With the revolving table I combine a spring-catch, which operates to stop the table in a proper position to receive the tile, and which 45 can be withdrawn to permit the next movement of the table. I have shown in the drawings one form of spring-catch, though others will readily suggest themselves, adapted to perform substantially the same operations. The 50 one shown consists of the laterally-moving piece J , which permits the plates to come successively up to a horizontal position, and a lateral part, J' , which prevents them from rising above said position until it (said part J') 55 has been intentionally withdrawn by the operator. The part J of the stop prevents the plates from moving downward while they are receiving the tiles. Both of these parts $J J'$ may be made in one piece of metal, as will be 60 readily understood. For some purposes, however, I prefer to construct them separately, as

shown, and provide each of them with an independent spring; part J being beveled or having its inner lower edge rounded, so as to permit the upward movement of the parts of the 65 revolving table, it (said part J) moving out of the path until the plate or trough has passed it, and then moving again below the plate or trough, this movement being caused by the spring j . The part J' is held across the path 70 of the plate or trough by means of a spring, j' . When the spring-catch is thus constructed and arranged I mount the parts thereof in a bracket-piece, K , carried by the frame of the revolving table.

To prevent the plates or troughs from being worn away by the action of the spring-catch, I provide each of them with wearing-plates $h h$, so situated that when the catch engages with the plates the contact shall be received by them.

With the revolving table, in order to get the best results, I combine a stationary trough or table, L , so situated as to first receive the tile as it issues from the mill and before it is cut. It is secured in position by means of angle-irons $l l$, which are slotted, as at l' , to receive the clamping-screws l^2 , whereby the trough L is secured to the frame. If vertical adjustment is necessary, it is permitted by the slots l' . As the tile issues from the mill I insert into the 95 end thereof a detachable cylinder or drum, M , of suitable length, the external diameter of which is substantially the same as the internal diameter of the pipe or tube of clay. I leave it there until the tile has been turned upon end, 100 after which I draw the drum through the tile from the end into which it was inserted to the other. The objects of this are, first, to keep the end of the tile from flattening as it runs along the trough; and, secondly, to form a perfect cylinder of clay, and remove or clean away the ragged edges that are generally left by the wire on the inside of the tile, in this way obviating the tedious process of trimming or finishing with a knife, which is now necessary. 110 The revolving table is adjusted in the rolling frame which carries it, the adjustment being effected by means of slots $d d$ in the sidepieces of the frame and the shaft D , which can be moved in said slots and secured in different 115 positions by means of clamping-nuts $d' d'$.

The drum or cylinder M is preferably constructed as shown—that is, with heads $m m$ and slats m' fastened thereto. In order to draw it easily through the tile, a handle may be attached to it, as shown in Figs. 4 and 5; or a separate handle may be used in withdrawing it, as shown in Fig. 7; but I do not limit myself to the use of such handles, as the purposes of the drum can be accomplished without such 125 a device.

What I claim is—

1. The combination, with the revolving table of a tile-mill having the plates or troughs $E E$, of the frame-work which holds said table, a 130 separate main frame, and rollers interposed between the two, whereby as the revolving

table is turned upon its axis it may be moved toward or from the tile-mill, substantially as set forth.

2. The combination, with the revolving table of a tile-mill having the plates or troughs E, of a spring-catch provided with a lower rounded or beveled edge, which permits each table in turn to pass upward, and provided with a flat stopping-edge above the rounded or beveled edge, which prevents the tables from moving downward, substantially as set forth.

3. The herein-described process of forming tiles of a tubular or concave form, it consisting in delivering a tube of clay from the tile-mill to a movable support, placing in the outer end of said tube a shaping and supporting device, then cutting off the tile at the required point, then lifting the tile into such position that the axis thereof shall be vertical, substantially as set forth.

4. The herein-described process of forming tiles of a tubular or concave form, it consist-

ing in first supporting a tube of clay from a tile-mill, inserting into the outer end of said tube a cylinder or drum, receiving said tube of clay upon a horizontal support, then cutting off said tile from said tube at the required point, then lifting the tile into a vertical position, and then drawing the aforesaid drum or cylinder through the tile, substantially as set forth.

5. The herein-described interior supporting and shaping device for the interior of clay tiles, it consisting of the drum or cylinder M, adapted to be inserted into the outer end of the tile as it is received from the mill, and to be drawn through it from the other end, substantially as set forth.

In testimony whereof I affix my signature in presence of two witnesses.

JOHN S. SMITH.
